UNITED STATES PATENT OFFICE.

THOMAS K. KEITH, DECEASED, LATE OF BOSTON, MASSACHUSETTS, BY HAROLD C. HUDSON, ADMINISTRATOR, OF SWAMPSCOTT, MASSACHUSETTS, ASSIGNOR TO UNITED SHOE MACHINERY COMPANY, OF PATERSON, NEW JERSEY, A CORPORATION OF NEW JERSEY.

TACKING MECHANISM.

1,030,819.

Specification of Letters Patent.

Patented June 25, 1912.

Original application filed April 24, 1897, Serial No. 633,693. Divided and this application filed October 29, 1910. Serial No. 589,681.

To all whom it may concern:

Be it known that THOMAS K. KEITH, late of Boston, in the county of Suffolk and State of Massachusetts, deceased, invented certain Improvements in Tacking Mechanisms, of which the following description, in connection with the accompanying drawings, is a specification, like reference characters on the drawings indicating like parts in the several figures.

This invention relates to machines for use in the manufacture of boots and shoes and particularly to tacking mechanism.

The invention is herein shown for exemplification as embodied in the tacking mechanism of a machine for working an upper over a last and securing the same, for which use the invention has been particularly designed, although many features of the invention are applicable also to tacking and nailing machines for general use.

The present application is a division of application Serial No. 633,693, filed April 24, 1897, in which is shown, in connection with the tacking mechanism, a lasting machine equipped with devices for working an upper into proper position upon a last and clamping the same in place while being tacked. Two jacks are mounted upon a carrier by movement of which the last carrying the prepared upper is brought into position to be operated upon by the tacking mechanism. Each jack is mounted for rotation about an axis perpendicular to the sole of the shoe at its middle portion and means is provided for automatically rotating the same.

By this invention a machine is provided in which the shoe support and the tacker mechanism have novel movements relative to each other.

Important features of the invention are embodied in the mechanism for moving the tacker head toward and over the edge of the insole by which movement the tacker head is brought into proper position for driving the tacks, and the upper may or may not be wiped in and laid down upon the insole by the tacker nose; and in the mechanism by which the tacker head is uplifted and retracted from its inserting position so that it clears the overlaid upper during its return to position for the next tacking movement.

A broadly novel feature of this invention which is of prime importance consists in provision for giving to the tacker an automatic movement longitudinally of the shoe so that at each operation the tacker head will act upon a new portion of the work. This longitudinal movement is herein utilized for moving the tacking mechanism along the sides of the shoe for the purpose of spacing the fastenings for the side portions of the upper. To carry on the tacking operation about the toe and heel portion of the shoe and to present the other side of the shoe to the tacking mechanism the last support is given a half-revolution when the toe is reached and also when the heel is reached. It is desirable for tacking along the second side of the shoe to have the tacker start from its initial position. Moreover, since the shoe rotates about an axis near its middle point, the toe portion, as the shoe rotates, has a movement back toward the initial position of the tacker. In accordance with a preferred arrangement embodying a further feature of this invention, advantage is taken of this rotation and backward travel of the toe portion for bringing the tacker mechanism back also to initial position for tacking the second side of the shoe. During the backward movement of the tacking mechanism, however, the rotative movement of the shoe is sufficiently in excess of the backward movement of the tacker mechanism so that the requisite relative movement is provided between the tacker and the shoe upper for placing the tacks in suitable spaced relation from each other. Furthermore, by this combined movement of the tacker and the shoe the tacker is made to pass over the edge of the shoe in a direction substantially perpendicular to the periphery at the point passed over.

Other features of the invention are found in the tack separating and feeding mechanism. The mechanism comprises a pivoted pick-off lever provided with an irregular slot in which a pin connected with the driver is arranged to reciprocate. The lower end of the lever is adapted for taking a tack from the end of the raceway and delivering it to the tacker head. The end of the pick-off lever is also adapted to move transversely across the raceway and form a clo-

sure therefor while delivering the tack to the driver. The end of the raceway is adjacent the driver and the end of the pick-off lever is provided with a notch adapted to take a tack from the raceway and deliver it to a tube leading directly to the driver, a lateral projection on the pick-off lever, meantime, holding the tacks in the raceway.

These and other features of the invention, 10 including certain details of construction and more important combinations of parts will appear in connection with the following description and will then be pointed out in the claims.

15 In the drawings in which an embodiment of the invention is illustrated for exemplification,—Figure 1 is a perspective view of the machine as a whole with part of the last- 20 ing mechanism broken away to show more clearly the parts with which this application is concerned; Fig. 2 is a side view in perspective of a portion of the machine; Fig. 3 is a plan perspective of a portion of the machine showing the tacker mechanism and the 25 last rotating means; Fig. 4 is a side elevation of the tacker mechanism; Fig. 5 is a sectional view taken through the tacker head and showing the driver and tack holding jaws; Fig. 6 is an enlarged detail section of 30 the tack holding jaws on the line 6—6, Fig. 5; Fig. 7 is a sectional view on the line 7—7 of Fig. 4; Fig. 8 is an enlarged detail section on the line 8—8 of Fig. 4; Fig. 9 is a detail of the bell-crank lever and adjacent 35 parts for swinging the tacker head; Fig. 10 is a detail view of the jack carrier locking mechanism, Fig. 11 is a detail view showing the stop mechanism in elevation as seen from the inside looking in the direction of the 40 main shaft; Fig. 12 is a detail of the catch on the last rotating lever; Fig. 13 is a detail perspective view of the tacker head.

The portion of the machine with which this invention is concerned is shown in general in Fig. 1 in which A is the base of the machine and 1 and 2 are columns for supporting various parts thereof, the tacker mechanism being arranged on the column 1. Standards 4 and 6 bolted to the base of the 45 machine carry respectively bearings for the main shaft 8 and the shaft 10, hereinafter referred to as the auxiliary shaft. For supporting the tacker mechanism a plate 12 is secured by bolts 13 to the top of the column 50 5. A rock-shaft 14 is supported in brackets 16 mounted upon the rear face of column 1. Secured to the rock-shaft 14 is an upwardly 55 extending arm 18 having a hole in its upper end in which is rotatably seated a pin 19 (Fig. 2) secured upon a plate 20, having ears at its ends which are pivoted by a pin 28 to ears 22 on a plate 26, which carries the tacker mechanism.

The plate 26 carries supports 30 having 60 65 bearings for a cam shaft 32 which has at one

end a sprocket wheel 34 over which passes a sprocket chain 36. The sprocket chain 36 passes also about one part of a double sprocket wheel 38 in line with sprocket wheel 34 and mounted for rotation upon a 70 stub shaft 40 supported by a bracket 42 on the rear face of the supporting column 1. Motion is communicated to the other part of the double sprocket wheel 38 by a sprocket chain 44 from a sprocket 46 fast on the main 75 shaft 8. A single rotation of the shaft 8, by this means, transmits one rotation to the cam shaft 32, the gear ratio being one to one. The shaft 32 which may be called the tacker cam shaft has fixed thereon edge cams 50, 60 80 and 70. The cam 50 actuates mechanism to operate the driver. The cam 60 through a system of levers communicates to the tacker head an in and out or to and fro movement over the edge of the last bottom. The cam 70 through its attendant mechanism gives to the tacker head a rising and falling or up and down motion. The action of the cams 60 and 70 is, however, interdependent and the motion of the tacker head is a resultant 85 of the two movements, the effect being to cause the nose of the tacker to move in a closed path.

Forward of the cam shaft 32 upon the tacker plate 12 are supports 80 for the opposite ends of a pintle rod 82 which passes through three cam levers 51, 61 and 71, and provides a common fulcrum therefor. The power ends of the levers carry cam rolls which engage respectively with the cams 50, 100 60 and 70.

The lever 51 at its forward end carries a link 52 pivotally connected to it and to a lever 53 fulcrumed intermediate its ends at 54 to the tacker head support 84. The forward end of the lever 53 is connected by a link 55 to a block 56 (Fig. 5) secured by a set screw upon the upper end of a driver bar 57. The driver bar carries at its lower end a driver 58 and the downward movement of the driver and driver bar is limited by a block 59 clamped to the driver bar by a set screw and having therebeneath buffer washers 81 to diminish the shock of the blow of the driver bar. The tacker head 110 support 84 is pivoted at 86 upon an inclined projection 88 from the forward end of the plate 12. A lever 78 is pivoted upon the upper end of the tacker head support 84 by the same bolt 54 as is the lever 53 of the 115 driver operating mechanism. To the forward end of the lever 78 is rigidly secured (Fig. 5) the tacker head 92. To the support 84 just above its pivot 86 is attached a bracket 94 carrying one end of the driver 120 spring 96 the other end of which is hooked through the lever 53 near its junction with the link 55 which connects it with the driver. From an inspection of Fig. 2 it will now be 125 clear that when the cam shaft 32 is rotated 130

by its sprocket chain connection with the main shaft 8 the cam 50 will act to raise the rear end of lever 51 and through the link 52, lever 53 and link 54 will raise the driver against the tension of the spring 96 and that when the cam roll on the lever 51 rides off the abrupt portion of the edge of cam 50 the driver will be released and will be forced downward by the spring 96 to drive a tack which is fed beneath the driver at each elevation thereof by mechanism to be subsequently described. The driver spring 96 being attached to the bracket 94 forward of the pivot 86 serves, besides the function described, to keep the cam roll of the lever 61 pressed against the cam 60 thus tending resiliently to keep the tacker head in its rearward position while the cam 60 forces it positively forward.

20 The in and out or to and fro movement of the tacker head is produced by the cam 60 acting on the end of lever 61 fulcrumed on the rod 82 as stated. The forward end of the lever 61 carries a pin 62 (Fig. 2) which engages a slot 63 in a rearwardly projecting arm 64 rigidly secured to the tacker head support 84 near its pivot 86. The cam 60 is shaped to oscillate the power end of lever 61 up and down once for each revolution of the cam shaft 32. This movement of the lever is communicated through the connections described to the arm 64 which being rigid with the tacker head support causes it to swing about the pivot 86. Assuming for the present that the lever 78 is rigid with the tacker head support 84, it will be seen that the nose of the tacker head is thus made to move about 86 as a center in an arc the horizontal component 40 of which extends across the edge of the last. It is this movement which enables the nose of the tacker head to pass over the edge of the last and press the upper down upon the same. To facilitate this operation the tacker head is provided with a shoe or wiper 98 which is upturned at its forward end so as to avoid catching on the clamps about the edge of the last, when these are used, during its in-wiping and down-rubbing action.

50 The up and down or rising and falling movement of the tacker head is communicated thereto from the lever 71 (Fig. 3) which is oscillated by a cam 70 similar in general to the cam 60. Upon the forward or inner end of the lever 71 is fixed at substantially right angles thereto and offset therefrom a T-shaped member 74 which has a slot 73 in the cross of the T adapted to engage a pin 75 carried by the lever 78. Upon the rear end of the lever 71 is an extension 76 extending beyond the cam shaft 32 to which one end of a spring 79 is attached. The other end of the spring is secured to the tacker plate. The spring, being under tension, holds the cam roll on the lever 71

in engagement with the cam 70 and through the connection described presses the tacker head down upon the work. The spring, however, renders this pressure yielding and enables the wiper on the nose of the tacker head to wipe over the clamps and hold the upper resiliently until secured by a tack. The cam 70 acts upon the lever 71 against the spring 79 to raise the rear end of said lever and to depress the T shaped member upon the forward end and also the rear end of lever 78 which is connected therewith by the slot 73 and pin 75. The forward end of the lever and the tacker head which it carries is thus raised and, when the cam 70 allows the spring 79 to react, is resiliently depressed upon the work.

From the coöperative relation of the parts connected with cam 60 and those connected with cam 70 it will be seen that starting with the tacker head lowered and about to move forward over the last the cam roller on the lever 71 will be substantially at a dwell of cam 70 and the T-shaped member stationary. Upon movement of the cam 60 from this point the lever 61 is depressed and the tacker head support 84 swung about its center of rotation 86. Supposing for the sake of explanation that this circular motion were to be communicated in toto to the nose of the tacker, that is, with no movement of the lever 78 about its pivot, it would be necessary to have in the T-shaped member 74 an arcuate slot corresponding to the movement of the tacker nose. In that case however the motion of the tacker head would have a vertical and a horizontal component, the vertical being the greater. For the purpose of moving the tacker head over the edge of the last only the horizontal component is desired with a slight vertical movement to press the nose of the tacker firmly down upon the upper. To partly neutralize this vertical movement, the slot 73 is made nearly horizontal but slightly inclined with its forward end the higher to permit depression of the tacker nose upon the upper when in tacking position and to neutralize an upward movement of the tacker due to the fact that the tacker support 84, being inclined to the rear when the tacker head is in retracted position, slightly raises the tacker head as it swings forward toward the vertical and brings the tacker head into tack driving position. After the tacker head has completed its inward movement over the last in a nearly horizontal direction as described and the tack has been driven, the cam 70 raises the tacker head by depressing the T-shaped member and the cams 60 and 70 then combine to move the tacker in a backwardly and downwardly curved path to its starting point.

The tack feeding, separating, and delivering mechanism will now be described.

Mounted upon the outer portion of the lever 78 which carries the tacker head on its inner end is a tack reservoir 100 from which a tack conduit 102 leads to a hopper 104. Intermediate the ends of the conduit 102 is a gate which comprises (Figs. 4 and 7) a bar 106 adapted to enter a slot in the conduit extending transversely thereof. One end of the gate bar 106 is pivoted at 108 to an offset 109 from the side of the hopper 104. The opposite end is held depressed with the gate in position to close the conduit by a spring 110 held under tension between the end of the bar 106 and a pin 112 extending from the side of the hopper (Fig. 7.) A bar 114 (Fig. 4) is pivoted at 86 with the tacker head support and has a slot 116 which engages a guiding pin 118 on the hopper. The upper end of the bar 114 engages the gate bar 106 near its end. As the tacker head moves downward about the pivot 54 to tack driving position there is relative movement between the gate bar 106 and the end of the bar 114, and the end 25 of the gate bar abutting thereagainst is accordingly raised and the gate opened to allow tacks to pass from the reservoir 100 to the hopper 104. The end of the conduit 102 (Fig. 7) is provided with a slot 120 on its under side and the tacks passing from the reservoir fall through the slot 120 upon an inclined raceway 122. The tacks which have their ends properly directed enter the raceway 122 and move down it toward the 30 tack separating device. The tacks which are not properly positioned to enter the raceway fall to the bottom of the hopper 104 and pass by a chute 124 to a receptacle 126 suitably mounted to receive them from 35 which they may be returned at intervals to the reservoir 100.

The pick-off lever 128 is pivoted to the front face of the tacker head at 132 and has its lower end extending to one side of the tacker head and bent rearwardly at right angles so that the tip of the lever which is provided with a notch 129 (Fig. 8) lies adjacent the end of the raceway 122 with its notch opposite the tack channel. The tip 45 has also a downwardly projecting lip 133 on its under side to prevent the end of a tack held in the notch from swinging laterally during the motion of the lever. The notch 129 is adapted to contain the body of the 50 lowermost tack in the raceway and is disposed to one side of the center of the end of the pick-off lever so that when the end of the lever 128 is moved in the direction of the arrow from its normal position it will 55 engage the lowermost tack with its notch and carry it to a position over the tube 130 leading to the driver passage while the unnotched position of the end of the pick-off lever will close the end of the tack raceway.

60 65 As the notch of the pick-off passes, with its

contained tack, beyond the end of the raceway the tack will drop from the notch or will be shaken off as the movement of the pick-off lever ceases and will enter the tube 130, which is preferably provided at its upper end, Fig. 13, with a funnel-shaped portion 131 having its side cut away to admit the lip 133 of the pick-off lever. The pick-off lever is provided above its pivot with an irregular slot 134 having two portions parallel with the driver bar connected by an oblique portion. The slot is engaged by a pin 136 upon a block 59 clamped to the driver bar 57 as previously described. As the driver bar is raised by the cam 50 through the mechanism described, the pin 136 passes up along the first parallel portion of the slot in the pick-off lever which remains stationary until the oblique portion of its slot is reached when the lever is oscillated upon its pivot to carry its notched end over the delivery tube 130. Then as the pin reaches the portion of the slot parallel to the first portion it suddenly stops and remains stationary during the remainder of the upward stroke of the driver bar. The tack, having been picked off and delivered to the tube 130 by the movements described, passes by gravity down the drive channel and is caught by the tack holding jaws 138 (Figs. 5 and 6) which are arranged to slide in and out in opposite holes in the nose of the tacker head. The meeting ends of the jaws 138 are provided with tapered grooves to form a tack holding recess 139 (Fig. 6) and are held resiliently in their inner or tack holding position by leaf springs 140. Each of these springs is secured at one end to the tacker head and at the other end has a squared notch adapted to engage the squared end of one of the jaws 138, and to abut against a shoulder 142. The jaws are then held from rotation with the larger end of the tapered tack holding recess 139 uppermost.

During the passage of the pin 136 along the upper parallel position of the slot the tack is given time to pass down the tube and assume its position in the tapered tack holding recess 139 before the descent of the driver. As the driver bar descends the pin 136 restores the pick-off lever to its normal position with its notch opposite the raceway and the driver strikes the tack and forces it through the jaws, which yield outwardly to 115 permit its passage, into the work upon the last.

By the mechanism thus far described the tacker head is given proper movements across, down to, and up from the last edge 120 to act upon an upper and the nails are arranged, separated, delivered and driven.

The relative movements of the tacker mechanism and the last support whereby the tacks are properly spaced about the pe- 125 130

riphery of the shoe sole are now to be described. The tacker mechanism is mounted upon the plate 26 which is pivoted at its rear end upon the upper end of the arm 18 mounted on the rock-shaft 14. At its forward end the tacker plate is provided with a block 27 which is in sliding engagement with the top of the column 1 when there is no work beneath the tacker head. Forward of the standard 80 on the plate 26 is attached an out-standing arm 144 (Fig. 3) to which is pivoted a bar 146. The other end of the bar carries a bolt and thumb nut which engage a slot 150 in the lever 152 pivoted at 154 to the top of the column 1. The opposite end of the lever 152 is pivoted to a block 156 which in turn is pivoted to the arm 158 (Fig. 9) which extends down within the column 1 through a slot 11 in its top plate 12 and is pivoted to a block 160 carrying a pin which engages a hole in the upper end of one arm 162 of a bell-crank lever pivoted at 164, the other arm 166 of which extends through an opening in the column 1 (Fig. 2) and rests upon a cam lever 168 intermediate the ends thereof. One arm of the lever 168 is pivoted to the standard 170 and the other carries a cam roll adapted to rest on a cam 172. A tension spring 174 is attached to a pin 176 on the arm 166 of the bell crank lever and to the base of the column 1 to hold the said arm against the cam lever 168. The cam 172 is fixed on the auxiliary shaft 10 journaled in the standard 6, as described and has two projections and two depressions about its periphery so that it produces two complete oscillations of the cam lever 168 for each revolution. Fixed on the same shaft is a ratchet wheel 178 and loose on the shaft is the arm 180 carrying the pawl 182 in engagement with the ratchet wheel 178 and connected between the pawl and its pivot by the connecting rod 184 with a crank 45 disk 186 on the main shaft 8. The face of the disk 186 is provided with a diametrically disposed dovetail slot in which the wrist pin 188 is mounted for adjustment for the purpose of varying the throw of the 50 pawl carrying arm 180 and pawl 182 so that the pawl may be made to pass one or more notches as the arm is reciprocated. The number of teeth in the ratchet wheel 178 corresponds to the maximum number of 55 tacks to be driven about the periphery of the shoe sole.

The operation of the above described mechanism is as follows: Supposing the main shaft to be rotated, the wrist pin 188 and connecting rod 184 will oscillate the arm 180 and cause the pawl 182 to rotate the ratchet wheel 178 one notch (if so adjusted) at each revolution of the main shaft, thus partially rotating the auxiliary shaft 60 10 and the cam 172 in counter clockwise di-

rection. Rotation of cam 172 from the position shown in Fig. 2 and in the direction indicated will raise the cam lever 168 and the arm 166 of the bell-crank lever resting thereon against the spring 174. The other arm 162 of the bell-crank lever will thus be oscillated and the arm 158 will push the inner end of the slotted lever 152 to the left in Fig. 3 and carry with it the end of the connecting bar 146 which is attached to the arm 144 on the tacker plate 26. The tacker head and its operating mechanism will thus be swung slightly to the left in Fig. 3 about the pivot 19 on the plate 20 and the next movement of the tacker head over the edge of the last will bring it into position to drive a tack at a point slightly displaced along the periphery of the last from the one last driven. This processive feeding movement of the tacker head will continue until the cam 172 has completed a quarter of its revolution and reached the limit of its first forward throw, then the tacker will begin to recede or travel back and will, of course, make two journeys in each direction for one revolution of the cam 172. The tacker reaches the limit of its movement toward the toe, however, at the point where the outline of the shoe sole begins to bend around the toe and as it begins to travel in the opposite direction the last support and shoe begins to rotate, due to mechanism to be described, in a counterclockwise direction at a rate which carries the toe portion backward faster than the tacker head moves, thus effecting the necessary relative movements between the tacker head and shoe to carry the tacking mechanism about the toe portion. Upon the completion of a semi-revolution of the last support the toe will have 105 been passed around and the tacker will be in position for movement along the second side of the shoe in the same direction as its first movement, but, as the position of the shoe is reversed, will, this time, travel from 110 toe to heel. When it reaches the heel the shoe support will be given another half revolution to enable the tacker to pass around the heel in a manner similar to its passage around the toe. The length of the steps 115 taken by the tacker head in its step by step movement along the edge of the last may be varied for different sized lasts by adjusting the end of the connecting bar 146 along the slot 150 in the lever 154.

The tacker head plate 26 is provided at its inner end with a gage or feeler 190 (Figs. 4 and 13) which engages the edge and top of the clamping plate or guide 191 which extends about the last to hold the upper in 125 place or which may rest against the upper itself in the absence of the plates. The gage 190 acts as an edge gage to limit the inward movement of the tacker head plate so that the tacks are located at the proper distance 130

from the edge of the last about the periphery of the shoe. The gage rests upon the top of the clamp or guide 191 which thus sustains a portion of the weight of the tacker head and carries a downwardly projecting lug 193 (Fig. 13) which is made to press against the side of the last or clamping plates by a weight 192 on the end of a cord 194 which passes over a pulley 196 and is attached to the tacker plate 26 near its rear end. The cord 194 passes also behind a pin 199 on the underside of the connecting bar 146 (Fig. 3) which arrangement properly directs the cord over the pulley and causes pressure on the pin to hold the tacker mechanism swung to the right in Fig. 3 thus assisting the spring 174. The feeler 190 serves as a rest for the tacker nose when the tacker is in retracted position, and as the tacker moves forward the nose is guided by the feeler over the guides 191 and under the impulse of the spring 79 slips off of the feeler and drops upon the upper with a blow, thus treating the upper by impact and beating it down upon the last. It then slides inward, wiping the upper down into position to be tacked. For moving the tacker mechanism backward out of the way of the last and support, a treadle lever 200 (Fig. 1) is provided pivoted about the main shaft and carrying at its rear end a link 202 having a cylindrical upper portion extending through a hole 204 in a lever 206 fixed on the rock-shaft 14, there being a shoulder on the link 202 for engaging the end of lever 206. Pressure on the forward end of the pedal lever will obviously rock the shaft 14 and carry the arm 18, plate 20 and tacker head plate 26 pivoted thereto backwardly. The arm 18 is held from lateral movement by the guides 21. The cylindrical upper portion of the link 202 engaging the hole 204 in the lever 206 permits the tacker head to be moved back if desired without operating the pedal lever.

The mechanism for rotating the shoe comprises a circular plate 220 which supports the jack and has its periphery divided into two portions of slightly different diameters, 50 the lower and larger portion having notches corresponding in number to the number of tacks to be driven about the heel and about the toe portions taken together. The plate 220 has a trunnion 218 in the center of its under side which passes through the end of the carrier member 240. A ring 241 is secured upon the trunnion and holds a spring 251 compressed against the carrier member 240. The spring 251 then holds the plate 220 resiliently against the carrier 240. Intermittent rotary motion is communicated to the plate 220 by connection with the main shaft best shown in Figs. 1 and 3. Mounted upon the main shaft 8 is an eccentric cam 226 which acts upon a bent lever 228. The

lever is held against the cam by a tension spring 229 attached at one end thereto between its pivot and the cam and at the other end to a pin on the column 2. Upon the upper end of the lever 228 is a device Fig. 12 comprising a plate 230 having a depending pin adjustably held by set screw 232 in a hole in the upper end of lever 228. The rear end of the plate 230 is upturned and has hinged thereto an upper plate 234. To limit the upward movement of the upper plate a stop 236 is attached to said plate, and has its lower end bent under the lower plate to limit the upper movement of the upper plate. A compression spring 238 suitably secured between the plates holds the upper plate against its stop but permits it to be depressed.

The jack carrier member 240 is mounted for rotation about its middle point upon the column 2. Duplicate jacks are provided, one upon each end of the member 240 so that a shoe may be prepared for tacking upon one of the jacks while another shoe is being automatically tacked on the other jack. The carrier 240 (Figs. 1 and 10) is locked in position with either jack adjacent the tacker by a bolt 242 slidably mounted in a member 244 attached to the column 2 (Fig. 1) and upheld by a loose pin connection 245 (Fig. 10) with a lever 246 fulcrumed at 248 and held upward by a spring 250. The bolt engages a recess in the downwardly projecting trunnion 218 of the jack plate and the end of the trunnion is beveled off so as to automatically depress the bolt 242 when brought in contact with the same, and allow it to snap into the recess therein. The bolt is drawn down for releasing the carrier by a rod 252, connected with the lever 246, passing through the pedal lever 200, and provided some distance below the same with a nut and washer. When the treadle is depressed the tacker mechanism is first moved back, as previously described, and then the lever encounters the washer and nut and withdraws the bolt to release the carrier 240.

As the jack is swung into position in front of the tacking mechanism the end of the lever 256 which operates its rotatory mechanism encounters the plate 234, depresses the same and allows it to snap back when passed. Subsequent movement of the lever 228 will cause the said plate 234 to engage and operate the lever 256. Referring to Fig. 3, it will be seen that the part of the lever 256 engaged by the plate 234 is the downwardly directed end of a bell-crank lever pivoted at 258 to the jack carrier 240. The end of the shorter arm of the bell-crank lever carries a pawl 260 adapted to engage teeth formed in the larger peripheral portion of the circular jack plate 220. The pawl 260 is held against the teeth of the jack plate by a tension spring 262 attached to a projecting heel 130.

of the pawl and to the lever 256 near its pivot. A second pawl 264 is mounted on the lever 256 and is adapted to engage a ratchet wheel 266 mounted for rotation on the axis 5 of the jack carrier and having attached to its lower face the cam plate formed with opposite cam projections 270. As a movement is given to the ratchet wheel 266 by the pawl 264 at each oscillation of the lever 10 256, the projections on the cam plate are periodically brought into contact with one end of a lever 272 pivoted intermediate its ends to the jack carrier and having its other end disposed above the larger peripheral 15 portion of the plate 220 and in front of the pawl 260 which is high enough to engage it. When one of the cam projections 270 engages the end of the lever 272 the other end pushes back the pawl 260 and renders it 20 inoperative so that the jack remains stationary as it must during the tacking of the comparatively straight sides of the shoe from heel to toe or from toe to heel. When, however, the toe or heel portion 25 (as the case may be) is reached, the cam projection will, as the rotation of the ratchet wheel 266 continues, ride off the end of the lever 272 and permit the pawl 260 to again engage the teeth in the base plate of the 30 jack and rotate it. A spring pressed pawl 273 is provided to prevent a backward movement of the jack plate 220. Similar rotating mechanism is, of course, provided for each jack. At the same time that the jack begins 35 to rotate, the cam 172 on the auxiliary shaft 10 reaches the limit of its throw and begins to permit movement of the tacker head, due to the spring 174 and counter weight 192, in the same direction as the edge of the shoe 40 next the tacker is being moved by the jack rotating mechanism. The motion due to the latter mechanism is, however, about twice that of the tacker head so the tacker head continues to move about the periphery of 45 the last at about the same rate as before.

The mechanism for starting and automatically stopping the machine is as follows:—A power driven pulley 280 is mounted loosely upon the main shaft 8 (Figs. 1 50 and 11) and has upon the face of the hub next the machine a plurality of ratchet teeth 282 adapted to engage an arm 284 projecting from a yoke 286 the ends of which are pivoted upon a pin 288 passing through 55 the main shaft. A spring (not shown) holds the arm of the yoke against the ratchet teeth when the machine is being driven. A lever 292 is pivoted to the base of the machine at 294 and has a projection 296 engaging a stop 60 plate 298 for limiting its rotation in response to a spring 300 which urges it to the right in Fig. 11. The end of the lever 292 is beveled off so that when it is permitted to swing to the right (Fig. 11) under the pressure 65 of spring 300 its end engages the simi- larly shaped end of the arm 284 on the yoke 286 and forces the same away from the ratchet teeth thus stopping the machine. For throwing the lever 292 out of the way of the arm 284 for starting the machine the lever 292 is provided with a projection 302 having an inclined face which is adapted to be engaged by a pin 304 on one arm 306 of a bell-crank lever pivoted on the main shaft. The other arm 308 of the bell-crank lever is 70 normally held, by pressure of the inclined projection 302 upon the pin 304, in an upright position but when swung to the left (Fig. 11) it presses the lever 292 back and frees the arm 284 so that it is spring pressed against the ratchet teeth 282. For swinging the arm 308 a slide rod 310 is provided having a handle 312 (Fig. 1.) within easy reach of the operator and carrying a pawl 314 (Fig. 1) held by a spring 315 in position to 75 engage the end of the arm 308. When the operator grasps the handle 312 and pushes it downward and away from him, the pawl 314 engages the arm 308 and moves it to the left in Fig. 11. A catch 316 is provided 80 near the handle 312 for holding the slide rod depressed and means is provided for automatically lifting the pawl 314 to stop the machine when the tacking operation has been performed entirely around the shoe. 85 A lever 318 is pivoted at 320 to an upright 90 322 and has at its rear end a pin 324 adapted to engage the edge of a cam 326 on the auxiliary shaft 10 which makes one revolution while the machine is going through the 95 operation of tacking entirely around the last. The forward end of the lever 326 has pivoted thereto a detent 328 (Fig. 11) having a stop 330 against which the detent is 100 pressed by a spring 332 attached between 105 a pin on the detent and a pin on the lever 318. When the machine is running the pin 333 on the pawl 314 is disposed over the end of the detent 328 so that the detent, when lifted, will engage the pin and lift the pawl. 110 Fig. 11 shows the position of the stop mechanism when the machine is running but is about to be stopped. When the cam 326 has rotated far enough in the direction indicated by the arrow the pin 324 on the lever 318 will reach the abrupt portion of the cam face and permit the rear end of the lever to be depressed by a spring 334 placed under tension between it and the base of the machine. The forward end of the lever presses 115 the detent 328 against the pin 333 and raises the pawl 314 releasing the arm 308 which is carried toward vertical position by the pressure of the inclined projection 302 of the lever 292 on the pin 304 carried by the arm 306. The lever 292 under the pressure of the spring 300 is carried into the path of the arm 284 which rotates with the main shaft and the said arm when it contacts with the beveled end of lever 292 is thrown out of en- 120 125 130

gagement with the ratchet teeth 282 and the machine stops.

In the operation of the machine as a whole the shoe is prepared for tacking by lasting mechanism partially shown at the left of Fig. 1 and fully described in the application referred to above but forming no part of the invention herein claimed. When a shoe is ready for tacking the operator depresses the pedal lever 200 which operates mechanism to withdraw the tacker head from contact with the shoe last tacked and to depress the locking bolt 242 and permit rotation of the carrier 240. The carrier is then rotated 180° to bring the shoe prepared for tacking into position adjacent the tacker and the shoe last tacked into position to be removed. Upon release of the treadle lever the tacker head is returned by the counterweight 192 into contact with the edge of the shoe at a predetermined point for example where the curve of the heel straightens into the shank portion. The operator now presses down the handle to start the machine. The tacker head is moved across the edge of the shoe, wipes down the upper, tacks it in place, is raised, retracted and lowered. During the retraction of the tacker head the arm 180 and pawl 182 are moved to the left (Fig. 2) to rotate the cam 172 and, through the system of levers described, advance the tacker head toward the toe a distance equal to the space between two tacks. When the tacker head has advanced in this manner along the side of the shoe to the point where the outline of the sole begins to bend around the toe, the last rotating mechanism is automatically thrown into operation and the shoe begins to rotate and the toe portion to travel backward toward the position initially occupied by the heel portion. At the said time, however, the tacker head begins to travel backward toward its initial position but at a slower rate than the periphery of the toe moves. The toe having been passed around and the opposite side of the shoe reached, the rotation thereof automatically ceases and the tacker head at the same time stops and resumes movement in the same direction as at first along the second side of the shoe, passing from toe to heel. When the bend of the heel portion is reached the shoe resumes its rotation and the tacker its return movement toward initial position at which it arrives when the heel has been passed around. During these movements of the tacker and shoe the cam 326 makes a single revolution and allows the pin 324 to ride off its abrupt portion which action results in the actuation of the stop mechanism as described.

While the invention is herein shown as embodied in a tack inserting mechanism, certain features of the invention are obvi-

ously broad enough to cover the insertion or application of any kind of fastening or similar device or the use of any other mechanism for uniting material.

Having now disclosed the inventive idea and described a machine embodying the same together with its mode of operation, I claim as new and desire to secure by Letters Patent of the United States:—

1. A machine of the class described having, in combination, a tacker, mechanism for moving the tacker inwardly over the edge of the shoe to tacking position and for pressing it downwardly as it is moved inwardly, and a guide over which the tacker moves in approaching the edge of the shoe and which is shaped to allow the tacker to drop down therefrom upon the shoe bottom, substantially as described. 75

2. A machine of the class described having, in combination, a tacker that has an in and out reciprocating movement over the shoe, and a feeler between which and the tacker there is provision for vertical and lateral movement arranged to ascertain the lateral and the vertical position of the tacker relatively to the portion of the shoe edge over which the tacker moves and to guide the tacker in accordance therewith. 85

3. A machine of the class described having, in combination, means for supplying and driving tacks in succession and power driving mechanism therefor including means to move the tacker automatically along the tacking line to space the tacks and laterally thereto into and out of tacking position. 95 100

4. A machine of the class described having, in combination, means for supplying and driving tacks in succession, power driving mechanism therefor including means to reciprocate the tack inserting devices from and toward tacking position, and means to move said devices laterally to space the tacks. 105

5. A machine of the class described having, in combination, means for supplying and driving tacks in succession, and power driving mechanism therefor including means to advance the inserting devices to inserting position, to actuate them to drive a tack, to retract them, and to move them laterally to space for the next tack insertion. 110 115

6. A machine of the class described having, in combination, means for supplying and driving tacks in succession, power driving mechanism therefor including means to actuate the inserting devices to drive tacks and to impart thereto between the tack insertions an intermittent movement along the tacking line to space tacks, and mechanism for effecting a relative in and out movement of the tack inserting devices and the shoe transversely of and across the shoe edge and 120 125

timed for the inserting devices and shoe to be out of contact during the tack spacing movement.

7. A machine of the class described having, in combination, means for supplying and driving tacks in succession, and power driving mechanism therefor including means to actuate the inserting devices to drive tacks and to impart thereto between 5 the tack insertions an intermittent movement along the tacking line first for a series of steps in one direction and then in the reverse direction.
8. A machine of the class described having, in combination, means for inserting separate fastenings and power driving mechanism therefor including means to cause the inserting means to travel along the inserting line to space the fastenings 15 automatically and means to move the inserting means laterally prior to each traveling movement.

9. A machine of the class described having, in combination, means for inserting 25 separate fastenings and power driving mechanism therefor including means to move the inserting means laterally in a curvilinear path between the inserting operations for spacing the fastenings.
10. A machine of the class described, comprising means for progressively working an upper over a last, means for securing the same, a revoluble carrier that may be turned when desired, a plurality of jacks 30 mounted on said carrier, each jack being provided with a toothed plate, a pawl carrier and a pawl to engage each of said toothed plates, and actuating means to insure the action of first one and then the other of said pawl carriers and its pawls according to which jack is to be rotated on the carrier, substantially as described.

11. A machine of the class described having, in combination, fastening inserting 45 means, actuating means to move the fastening means step by step in one direction to space a series of fastenings along the edge of a shoe and then in the opposite direction, said fastening means comprising a support 50 with which it is movable in and out for following the contour of the last, and means for effecting additional movements of the fastening means on its support in and out over the last edge in substantially the direction of said last mentioned movement.

12. A machine of the class described having, in combination, fastening inserting means, means to impart thereto an in and out movement and means to impart to the 60 fastening inserting means a traveling movement substantially parallel with the side of a shoe presented to the machine.

13. In a machine of the class described, a 65 shaft adapted to be power driven, an auxiliary shaft, means connecting the power shaft

with the auxiliary shaft for giving the same one rotation for a predetermined number of rotations of the power shaft, a pivoted tacker plate, a tacker mounted thereon, means for actuating the tacker from the power shaft, and means connected with the auxiliary shaft for swinging the tacker plate on its pivot. 70

14. In a machine of the class described, a power shaft, an auxiliary shaft, a ratchet wheel thereon, a pawl engaging said ratchet wheel, an adjustable crank pin connected with the power shaft, connecting means between the crank pin and said pawl, a pivoted tacker plate, a tacker head and its operating mechanism mounted thereon, connections between the power shaft and said operating mechanism for actuating the same, and means between the tacker plate and the auxiliary shaft for oscillating the 75 tacker plate. 80

15. In a machine of the class described, a tacker plate, tacker mechanism mounted thereon, a mounting for the tacker plate whereby it is free to oscillate to produce 90 travel of the tacker mechanism and to move bodily longitudinally of itself for moving the tacker transversely of the edge of a shoe sole, means independent of the movements of the tacker plate for actuating the tacker 95 mechanism, and means for oscillating the tacker plate step-by-step. 100

16. In a machine of the class described, a power shaft, an auxiliary shaft, a ratchet wheel thereon having a number of teeth corresponding to the maximum number of tacks to be driven about the periphery of a shoe sole, means for moving said ratchet wheel one or more teeth at each revolution of the power shaft, a traveling tacker and means connected with the auxiliary shaft 105 for communicating motion to the tacker. 110

17. In a machine of the class described, a main shaft, an auxiliary shaft, means for communicating intermittent rotative movement to the auxiliary shaft at each revolution of the main shaft, a tacker support, a tacker head mounted for movement longitudinally of a shoe on the support, a cam on the auxiliary shaft and lever connection 115 between the cam and the tacker head whereby the tacker head is moved relatively to the shoe in timed relation to the rotations of the main shaft. 120

18. In a machine of the class described, a main shaft, an auxiliary shaft, means for rotating the same once for a predetermined number of rotations of the main shaft, a cam on the auxiliary shaft, a movable tacker and lever connections between said tacker 125 and said cam whereby step-by-step movements are given to the tacker in time relation to the rotation of the main shaft. 130

19. A machine of the class described having, in combination, a shaft adapted to be

continuously rotated by power during the cycle of the machine, an auxiliary shaft, means connecting the power shaft to the auxiliary shaft whereby the latter is rotated once during the cycle of the machine, a tacker plate, a tacker mounted thereon, means for actuating the tacker connected with the power shaft, means for moving the tacker plate connected with the auxiliary shaft, a stop mechanism connected with the power shaft and means connected with the auxiliary shaft for tripping the stop mechanism at the end of the cycle of the machine.

15. 20. In a machine of the class described, a support, a tacker plate, a rock-shaft on the support, an arm on the rock-shaft, a plate, pivotal connections between said arm and said plate and between said plate and said tacker plate, a tacker head mounted on said tacker plate, a cam shaft on said tacker plate; connections between said tacker head and said cam shaft for moving the nose of the tacker head in a closed path and for operating the driver, means for rotating the cam shaft and means for oscillating the tacker plate in time relation to rotations of the cam shaft.

21. In a machine of the class described 30 the combination of a tacker head mounted for oscillation, means for operating the driver, means for advancing the nose of the tacker over an upper and retracting the same, means for raising the tacker and 35 means for lowering the tacker simultaneously with the retraction, and means for oscillating the tacker head in time relation to the movements of the tacker nose.

22. A machine of the class described comprising a tacker mounted for oscillation and 40 for movement toward and from a shoe, a shoe embracing member, a gage on the tacker adapted to engage a portion of the shoe embracing member for limiting the 45 movement of the tacker toward the shoe, means for yieldingly pressing the guide against said member, means for giving the tacker head movement over the edge of the shoe, and means for oscillating the tacker 50 step-by-step in alternation with its movement over the edge of the shoe.

23. A tacker plate, a cam shaft on the tacker plate carrying a driver cam, an advancing cam, and an elevating cam, a tacker 55 head support pivoted to said tacker plate, a driver lever and a tacker head lever pivoted to said support, connection between said driver lever and the driver and between the driver lever and the driver cam, connection 60 between said tacker head lever and the elevating cam, and connection between the tacker head support and the advancing cam for moving it upon its pivot.

24. In a machine of the class described, a

main shaft, an auxiliary shaft, means for 65 intermittently rotating the auxiliary shaft in predetermined relation to the main shaft, a tacker plate pivoted at its rear end, a substantially elliptical cam fixed centrally on the auxiliary shaft, levers connecting said 70 cam with the forward end of the tacker plate and means for varying the amount of movement communicated to the tacker plate by said cam through said levers.

25. In a machine of the class described, a 75 main shaft, an auxiliary shaft, means for intermittently rotating the auxiliary shaft in predetermined relation to the main shaft, a tacker plate pivoted at its rear end, a substantially elliptical cam fixed centrally on the auxiliary shaft, levers connecting said 80 cam with the forward end of the tacker plate, means for varying the amount of movement communicated to the tacker plate by said cam through said levers, a 85 tacker on said tacker plate and means for actuating the tacker from the main shaft.

26. In a machine of the class described, a tacker plate, a tacker head, a tacker head support pivoted on said plate, means for 90 rocking said support on its pivot, means for converting the curvilinear motion of the tacker head due to said rocking movement into substantially rectilinear movement inward across the edge of the shoe sole, means 95 for actuating the driver to drive a tack when the tacker is in its inward position, means for raising the tacker head and means for returning it to its initial position.

27. In a machine of the class described, a 100 column, a rock-shaft mounted on the rear face of said column, an arm extending upward from said shaft, guides for limiting the lateral movement of said arm, a plate pivoted to said arm, a tacker plate hinged to 105 said plate, a shoe support, and yielding means for pressing the tacker plate toward said support.

28. In a machine of the class described, a tacker head, a driver, a driver spring normally under tension, means for moving the tacker head inward over a shoe bottom and permitting retraction of said head under the tension of the driver spring.

29. In a machine of the class described, a 115 shoe support, means for imparting to the same intermittent rotation, a tacker head, means for guiding the tacker head in predetermined relation to the edge of the shoe sole laterally and vertically, means for giving the tacker head movement in the plane of the sole, means for moving the tacker head in a closed path lying in a plane perpendicular to the sole.

30. A machine of the class described, comprising a tacker head, means extending about the periphery of the shoe for guiding the tacker head in operative relation to the

- edge of a shoe both vertically and horizontally, means for giving the tacker head a forward movement over the guide onto the upper, means for operating the tacker while 5 on the upper and means for retracting the tacker head out of contact with the upper.
31. A machine of the class described comprising means for wiping in the upper, 10 means for uniting the same to the innersole, said two means being adapted to operate progressively around a shoe, a revoluble carrier that may be turned when desired, a plurality of jacks mounted thereon, each 15 jack being provided with a toothed plate, a plurality of pawl carriers having each a pawl to engage one of said toothed plates combined with actuating means to actuate first one and then the other of said pawl 20 carriers according to which jack is to be rotated, a pawl controller and means to operate it to at times suspend the operation of one of said pawls when rotating said jack in order that said jack may remain at rest be- 25 tween each semi-rotation for a period of sufficient length to enable the upper along the straight side of the last in the jack to be united to the innersole by said uniting means, substantially as described.
32. A machine of the class described, having in combination, a shoe support, rotatable about a single fixed axis, and mechanism for uniting the upper to the inner sole which has automatic in and out movements to 35 enable it to follow the edge of the shoe around an end and along a side.
33. A machine of the class described, having in combination, a shoe support rotatable about a single fixed axis located in the 40 longitudinal center of the shoe, and tacking mechanism which has automatic in and out movements to cause it to follow the edge of the shoe around the ends and sides and means for actuating the support and the 45 tacker, substantially as described.
34. A machine of the class described comprising a shoe support arranged to turn about a fixed center, a tacking mechanism arranged to move in and out with respect to said sup- 50 port to insert a row of tacks along the edge of a shoe supported thereon, said tacker being movable also in a direction transverse to the direction of its in and out movement to space the tacks along the edge of the shoe 55 where the turning of the support does not cause a relative traveling movement of the shoe and tacking mechanism.
35. In a machine of the class described, mechanism for inserting lasting tacks in a 60 shoe bottom, a circularly movable carrier and a plurality of jacks mounted thereon and provided with devices for pressing the sides and toe and heel of the upper against the lasts on said jacks, combined with means to automatically rotate said jacks and said devices on said carrier for presentation of the upper of the shoe to said mechanism, substantially as described.
36. In a machine of the class described, the combination of a movable carrier, a plu- 65 rality of jacks mounted thereon and pro- 70 vided with devices for pressing the sides and toe and heel of the upper against the lasts on said jacks, independent means to impart to each of said jacks and said de- 75 vices in succession two semi-rotations leav- 80 ing them at rest for a period between each of said semi-rotations, a bed, and means mounted thereon for uniting the upper to the innersole, means to move said bed and innersole uniting means longitudinally first in one and then in a reverse direction.
37. A machine of the class described, comprising means for progressively working an upper over a last, means for securing the 85 same, a revoluble carrier that may be turned when desired, a plurality of jacks mounted on said carrier and having hubs, a locking device to engage said hubs in succession after each movement of the carrier and lock 90 the carrier in operative position, and a tre- 95 dle to unlock said locking device to release the carrier when it is to be moved to change the positions of the jacks, substantially as described.
38. In a machine of the class described, a bed-plate, means carried thereby for uniting the upper to the innersole, a yoke on which 100 said bed is pivoted, a lever on which said yoke is pivoted, and means to move said lever and bed to put into and out of operative position said means for uniting the upper to the innersole, substantially as described.
39. In a machine of the class described, a bed-plate, means carried thereby for uniting 105 the upper to the innersole, a yoke on which said bed is pivoted, a lever on which said yoke is pivoted, and means to move said lever and bed to put into and out of operative position said means for uniting the upper to 110 the innersole, and means to slide said bed laterally, substantially as described.
40. In a machine of the class described, a bed-plate, means carried thereby for uniting 115 the upper to the innersole, a yoke on which said bed is pivoted, a lever on which said yoke is pivoted, and means to move said lever and bed to put into and out of operative position said means for uniting the upper to the innersole, and a jack for holding a lasted 120 shoe, substantially as described.
41. In a machine of the class described, a bed-plate, means carried thereby for uniting 125 the upper to the innersole, a yoke on which said bed is pivoted, a lever on which said yoke is pivoted, and means to move said lever and bed to put into and out of operative position said means for uniting the upper to

- the innersole, means to slide said bed laterally, and a jack for holding a lasted shoe, substantially as described.
42. In a machine of the class described, a 5 jack for holding a lasted shoe, and a tacker head having a driver, means whereby the tacker head has imparted to it four motions and means for actuating said driver to drive a tack when the said head is in position with 10 its nose on the upper, substantially as described.
43. In a machine of the class described, the combination of a shoe support, fastening inserting means, and means for imparting 15 to one of said parts a substantially semi-rotation about a vertical axis, and to the other a traveling movement in different directions substantially parallel with the length of the shoe sustained in the shoe support, said devices coöperating to insure the action of the 20 fastening means along the opposite ends and sides of a shoe on said support.
44. In a machine of the class described, the combination of a shoe support, traveling 25 fastening driving means adapted to drive fastenings in the process of lasting said mechanism for moving said driving means parallel with relation to the edge of one side of the shoe toward the toe and then toward 30 the heel end thereof in presenting and inserting fastenings at different points about the shoe with relation to its length.
45. In a machine of the class described, the combination of an automatically rotatable 35 shoe support, fastening inserting means, and actuating means to move said fastening means in opposite directions substantially parallel with the adjacent portion of the edge of the shoe carried by said support.
46. In a lasting machine, a plurality of 40 shoe supports to sustain lasts having shoes to be lasted, means to partially rotate each support when it is in position to have the upper of the shoe thereon tacked in place, 45 traveling tack driving means, and devices to impart thereto an in-and-out and a rising and falling movement between each tack driving operation and the succeeding tack driving operation.
47. In a lasting machine, fastening inserting means and devices to impart to the same in-and-out, rising and falling and traveling movements.
48. In a machine of the class described the 55 combination of a shoe support to sustain a last, and fastening driving means, one having a circular movement about an axis substantially perpendicular to the bottom of the last sustained by said shoe support, the other 60 having a traveling movement in different directions along the shoe edge, and automatic means for operating said parts to insure the action of the fastening means along the opposite sides of a shoe on said support.
49. In a machine of the class described, 65 the combination of a jack combined with a last to hold the shoe to be lasted, a tacker head having a driver, means to impart to said tacker head four motions during one cycle of the machine's operation, means to 70 actuate the driver in the tacker head to drive a tack when the nose of the head rests on the upper, and means to change the relative positions of said jack carrying the last and the tacker head that tacks may be driven along the edge of the last to unite the upper to the innersole thereon.
50. In a machine of the class described, the combination of a shoe support and fastening inserting means, one having a rotative movement about a substantially vertical pivot located between the toe and heel of the last held in said support, and the other a traveling movement in the direction of the length of the edge of the sole of the shoe 80 sustained in said shoe support, and automatic operating means to cause relative travel of said fastening means about a shoe 85 carried by said support.
51. In a lasting machine a fastening inserting means, a plurality of individually, automatically rotatable last supports, and means to sustain the same that said supports may be brought as desired in position one after the other that the uppers of the shoes 90 sustained by the lasts on said supports may be secured by fastenings.
52. In a lasting machine, a plurality of shoe supports to sustain lasts having shoes to be lasted, means to impart circular movement for a distance less than the circumference of a circle to said shoe supports when occupying positions for fastening the uppers of the shoes to the innersoles laid on the lasts sustained by said shoe supports, means 100 to arrest the movement of said shoe supports between one and its next circular movement, traveling fastening inserting means, and devices to impart thereto in-and-out and rising and falling movements between the operations of inserting the fastening.
53. In a machine of the class described, tacking means, a centrally pivoted carrier, a plurality of jacks mounted thereon including each a foot plate having a connected 115 ratchet wheel provided with a hub, each of said foot plates having a heel pin and devices to press the upper against the sides of the last, means to lock the ratchet wheel of said jack in place while a shoe on a last is 120 being applied to the jack, and means to subsequently rotate said jacks step by step in said carrier when said jack occupies a position such that the shoe on its last may receive tacks from the tacking means.
54. In a machine of the class described, tacking means including a movable tacker head, a carrier sustaining a plurality of jacks, means to impart a step by step semi- 125 rotation to each of said jacks while in posi- 130

tion to receive tacks from the tacking means, a treadle, and means controlled thereby to insure the backward movement of the tacker head that it may be carried out of operative position while the carrier is being moved from one into its other position, substantially as described.

55. A machine of the class described, comprising a tacker head, means for guiding the same in operative relation to the edge of a shoe both vertically and horizontally, means for giving the tacker head a forward movement over the guiding means and on to the upper, means for operating the tacker 10 while on the upper, means for retracting the tacker head out of contact with the upper, means for giving the tacker head intermittent processive and intermittent recessive movements along the shoe edge, means for 15 holding the shoe stationary during the processive movements and means for moving intermittently the periphery of the shoe adjacent to the tacker during its recessive movements at a rate in excess of said recessive movements.

56. In a machine of the class described, a rotatably mounted shoe support, upper securing means having movements from and toward inserting position and movements to 20 space the inserting points and means for automatically rotating the shoe support in time relation with said spacing movements.

57. In a machine of the class described, a shoe support mounted for rotation, a tacker 25 plate mounted for movement in a plane substantially parallel with the shoe sole, a tacker mechanism carried on the tacker plate, means for moving the tacker mechanism over the shoe sole in a plane substantially perpendicular thereto, means for giving the tacker plate oscillating movements, said movements taking place step-by-step in time relation to the operation of the tacker mechanism, means for rotating the shoe support and means for rendering the rotating 40 mechanism inoperative for periods in time relation to the direction of oscillation of the tacker plate.

58. In a machine of the class described, a shoe support mounted for rotation, a tacker plate mounted for movement in a plane substantially parallel with the shoe sole, a tacker mechanism carried on the tacker plate, means for oscillating the tacker plate 55 to carry the tacker mechanism along the shoe edge to space the tacking operation, means for rotating the shoe support and means for causing dwells in the movement of the shoe support while the tacker plate 60 continues in operation.

59. In a machine of the class described, a shoe support, a tacker mounted for movement to space tacks between inserting operations, and means operating automatically 65 to impart to the shoe support spacing move-

ments during certain tacker movements and to maintain the support at rest at other times.

60. In a machine of the class described, a shoe support, a tacker mounted for movement to space tacks between inserting operations, and means operating automatically to impart to the shoe support spacing movements in the direction of said spacing movements of the tacker.

61. In a machine of the class described, a shoe support, a tacker mounted for movement to space tacks between inserting operations, and means operating automatically to impart to the shoe support spacing movements in the direction of said spacing movements of the tacker but in excess thereof.

62. In a machine of the class described, a shoe support, a tacker, means to move the tacker in one direction to space the tacks between a succession of inserting operations and then similarly to move the tacker in the reverse direction to return it to the starting position, and means for imparting to the shoe support during the return movements 90 of the tacker spacing movements in the same direction as those of the tacker and of greater length.

63. In a machine of the class described, a rotatable shoe support, a tacker mounted for movement substantially parallel to the plane of the shoe sole, means for guiding the tacker in predetermined vertical relation to the shoe bottom, means for moving the tacker continuously to and fro along the 100 shoe edge, means for rotating the shoe support intermittently and means for causing said intermittent movement to cease simultaneously with the change of direction of the tacker movement.

64. A machine of the class described, comprising a tacker head, means for giving the same processive and recessive movement along a shoe edge, and means for moving the shoe during recessive movement of the tacker at such a rate as to produce progression of the tacker about the periphery of the shoe.

65. A machine of the class described, having in combination, a shoe support, a pawl 115 for actuating the shoe support, means for giving intermittent motion to the pawl continually, means rendering said pawl inoperative for predetermined intervals, traveling securing means having processive and recessive movements, said processive movements taking place while said pawl is inoperative.

66. A machine of the class described, comprising a tacker mechanism, a shoe support 125 mounted upon a plate provided with teeth and adapted to rotate upon an axis perpendicular to the shoe sole, a pivoted carrier for said shoe support, a ratchet wheel on the axis of said carrier, a bell crank mounted on 130

said carrier and carrying a pawl adapted to engage the teeth on said ratchet, means for oscillating said lever for each operation of the tacker mechanism, a second pawl on said lever adapted to engage the teeth on said plate, a lever pivoted to said carrier arranged to engage said second pawl, and a cam on said ratchet wheel adapted to engage said lever to disengage said second pawl from said teeth.

10 67. In a shoe machine, the combination of means for automatically driving tacks, means for supporting a shoe, means for moving the tacking mechanism longitudinally of the shoe, and means for rotating the shoe support upon an axis perpendicular to the plane of the shoe sole at its mid portion.

15 68. In a shoe machine, having a shoe support and automatic wiping in and tacking mechanism, the combination of means for moving the shoe relatively to the said mechanism and means for moving the said mechanism relatively to the shoe whereby the direction of movement of the said mechanism over the sole edge is maintained substantially normal to the periphery of the sole at the point wiped over.

20 69. In an automatic machine for tacking shoes, a tacker head, means for moving the same along the shoe edge, means for moving the shoe edge adjacent the tacker faster than the tracker, means for reversing the movement of the tracker, and means for stopping the movement of the shoe edge when the tacker movement is reversed.

25 70. In an automatic shoe tacking machine, the combination of a shoe support, means for rotating it, a tacker, means for moving the tacker nose in a closed path and means for giving the tacker a traveling movement.

30 71. In a machine of the class described, a rotatable jack carrier, means for locking the same, a movable tacker and connected means for withdrawing the tacker from contact with the shoe and unlocking the carrier for rotation.

35 72. In a machine of the class described, a last support, a tacker plate pivoted at its rear end at B⁵, a tacker head mounted upon the forward end of the tacker plate, means for oscillating the tacker plate on its pivot and means for moving the nose of the tacker head in a closed path.

40 73. In a machine of the class described, a last support, a tacker plate pivoted at its rear end, a tacker head mounted upon the forward end of the tacker plate, means for oscillating the tacker plate on its pivot and means for moving the nose of the tacker head in a closed path lying in a plane transverse of and perpendicular to the shoe sole.

45 74. A machine of the class described hav-

ing, in combination, a column, a plurality of shoe supports mounted for rotation thereon about a common axis into position adjacent to a tacker, and a tacker movable into and out of tack inserting position over the shoe on the adjacent support. 70

75 75. A machine of the class described, having in combination, a column, a plurality of shoe supports thereon movable alternatively into and out of position for the shoes to be tacked, each of said supports being rotatable on its own axis, and a tacker movable from and toward the adjacent shoe to tack on different portions of the shoe as the support is rotated. 75

80 76. A machine of the class described having, in combination, a column, a plurality of shoe supports thereon movable alternatively into and out of position for the shoes to be tacked, each of said supports being rotatable on its own axis, a tacker support movable toward and from the adjacent shoe to position the tacker for the portion of the shoe that is to be fastened, means for holding the tacker support yieldingly toward the adjacent shoe, and means for actuating the tacker relatively to the support to carry it back and forth over the shoe. 85

90 77. A machine of the class described having, in combination, a column, a carrier rotatable thereon, a plurality of jacks rotatable with the carrier and each rotatable also about its own axis, and operating means with relation to which the carrier is turned to present the jacks singly and with relation to which the presented jack is turned to present different parts of the shoe in position to be operated upon. 95

100 78. A machine of the class described having, in combination, a jack for holding a shoe, a tacker, means for actuating the tacker forwardly and backwardly across the shoe edge from and toward inserting positions, and means for actuating the tacker laterally to space the tacks between tack inserting operations. 105

110 79. A machine of the class described having, in combination, a shoe support, and a tacker that comprises an inclined driver casing with an upper wiping nose and is mounted for vertical movement to adapt itself to the height of different portions of the bottom of the shoe on the support, and means to impart to the tacker inward wiping movements over the shoe bottom and return movements. 115

120 80. A machine of the class described having, in combination, a shoe support and a tacker that comprises a driver casing and an upper wiping member and is mounted for oscillation in-and-out over the shoe bottom about a center which is located below the plane of the bottom of the shoe in the support and back of it whereby the path of the tacker and the wiping member in go- 125

130

ing inwardly over the shoe is inclined downwardly.

81. A machine of the class described having, in combination, a shoe support and a tacker that comprises a driver casing and an upper wiping member and is mounted for oscillation in and out over the shoe bottom about a center which is located below the plane of the bottom of the shoe in the support and back of it whereby the path of the tacker in going inwardly over the shoe is inclined downwardly, and means to cause the driver to insert a tack inclined inwardly while the wiping member is applying maximum downward pressure upon the overwiped shoe upper.

82. A machine of the class described having, in combination, a shoe support, a tacker that is movable vertically and longitudinally to follow the contour of the shoe edge and insert tacks in the shoe bottom, and a guide around the perimeter of the shoe bottom, said guide having side and top faces for guiding the tacker in its movements relatively to the shoe.

83. A machine of the class described having, in combination, means for operating on a shoe and means for positioning the shoe relatively to said means and comprising an edge gage which is mounted to yield upwardly and backwardly about separate axes.

84. A machine of the class described having, in combination, a shoe support, a tacker, means for giving the same an in and out reciprocating movement over the shoe on said support, a feeler on which said tacker normally rests in its inward position and from which it descends upon the shoe when moved to its outward position.

85. A machine of the class described having, in combination, a shoe support, a tacker, means for giving the same an in and out reciprocating movement over the shoe on said support, means for resiliently depressing the tacker upon the shoe, and a feeler adapted to support said tacker against said depressing means when in inward position and to permit the same to drop down upon the shoe when moved into outward position.

86. In a machine of the class described, a shoe support, guiding means surrounding the shoe support and conforming to the contour of the sole edge, a tacker support adapted for in and out and up and down movement relatively to the shoe, a feeler on said support adapted to engage said guiding means, a tacker, means for resiliently depressing the tacker head upon said feeler, and means for moving the tacker head over the shoe and off of said feeler whereby the tacker is caused to wipe over the shoe upper and drop suddenly thereupon as it leaves the feeler.

87. In a machine of the class described, a shoe support, a resiliently depressed tacker,

means for raising the tacker, means for advancing and retracting the tacker over the shoe support, and means normally holding said tacker elevated and permitting it to be depressed when in advanced position.

88. A machine of the class described having, in combination, a shoe support, a tacker, a wiper, mechanism for actuating the wiper inwardly across the edge of the shoe and pressing it downwardly, and means for maintaining the wiper above the plane of the shoe bottom until it reaches the edge of the shoe and then permitting it to drop under said downward pressure upon the shoe bottom to treat the shoe by impact preliminary to the insertion of a tack from the tacker.

89. A machine of the class described having, in combination, a shoe support, a wiper, mechanism for moving the wiper inwardly over the edge of the shoe to wiping position, and for pressing it downwardly as it is moved inwardly and a guide over which the wiper moves in approaching the edge of the shoe and which is shaped to allow the wiper to drop down therefrom upon the shoe bottom, substantially as described.

90. A machine of the class described having, in combination, a combined tacker and wiper having a movement forwardly over the edge of a shoe, said machine being arranged to cause the wiper to move forwardly with a downward pressure, and means for relatively positioning the wiper and shoe arranged to cause the wiper to drop upon the shoe bottom with an impact during its forward movement.

91. A machine of the class described having, in combination, a shoe support, a wiper, mechanism for moving the wiper inwardly over the edge of the shoe to wiping position and for pressing it downwardly as it is moved inwardly, a guide over which the wiper moves in approaching the edge of the shoe and which is shaped to allow the wiper to drop down therefrom upon the shoe bottom, and means for lifting the wiper from the shoe to prevent drag during its return movement.

92. A machine of the class described having, in combination, means for operating on a shoe having the wiping member movable across the shoe edge under downward pressure, and means for determining the lateral position of the shoe and the relative vertical positions of the wiping member and the shoe and being formed to permit the wiping member to descend by impact upon the shoe bottom during its forward stroke.

93. A machine of the class described having, in combination, means for operating on a shoe having the wiping member movable across the shoe edge under downward pressure, means for determining the lateral position of the shoe and the relative

vertical portion of the wiping member and the shoe and being formed to permit the wiping member to descend by impact upon the shoe bottom during its forward stroke, and means for raising said wiping member preparatory to a repetition of its forward stroke.

94. A machine of the class described having, in combination, a wiper, means for actuating it forwardly with a downward pressure until it reaches the edge of a shoe, and then dropping it to strike the shoe by impact and continuing its forward movement.

95. A machine of the class described having, in combination, a shoe support, a tacker that is movable over the shoe on said support and pressed yieldingly toward the shoe support to a variable position determined by the edge contour of the shoe, means to uplift the tacker and means to retract the tacker a predetermined distance while it is uplifted.

96. A machine of the class described having, in combination, a shoe support, a tacker sustaining means, a tacker that is movable over the shoe on said support and pressed yieldingly toward the shoe support to a variable position determined by the edge contour of the shoe, means to retract the tacker after each driving operation to permit relative feeding movements, and a gage movably mounted on the tacker sustaining means and yieldingly actuated to maintain constantly an operative relation to the shoe.

97. A machine of the class described having, in combination, a shoe support, a tacker sustaining means, a tacker that is movable over the shoe on said support and pressed yieldingly toward the shoe support to a variable position determined by the edge contour of the shoe, means to retract the tacker after each driving operation to permit relative feeding movements, and a gage mounted on the tacker sustaining means to yield upwardly and backwardly and arranged to maintain constant operative relation vertically and laterally with the shoe during the movements of the tacker.

98. A machine of the class described having, in combination, a last support, a tacker, and actuating mechanism for both including means for effecting at one time a traveling movement of the tacker alone and at another time a traveling movement of both the last support and the tacker.

99. A machine of the class described having, in combination, a last support, a tacker, and actuating mechanism for both including means for effecting at one time a traveling movement of the tacker alone and at another time a traveling movement of the last support in one direction and of the tacker in the same general direction, but through a different distance, between the insertion of successive tacks.

100. A machine of the class described having, in combination, a last support, a tacker, and actuating mechanism for both including means for effecting a traveling movement of the tacker and a traveling movement of the last support in the same direction between the insertion of two successive tacks.

101. A machine of the class described having, in combination, a last support, a tacker, and actuating mechanism for both including means for effecting a traveling movement of the tacker and a traveling movement of the last support in the same direction and of such length between two adjacent tacks that the tacks will be appropriately spaced apart and the tacker will progress from one side of the machine toward the other.

102. A machine of the class described having, in combination, a last support, a tacker, and actuating mechanism for both including means for effecting a traveling movement of the tacker toward one side of the machine, then a traveling movement of the last support and the tacker together toward the opposite side of the machine but at different rates of speed whereby the tacks are spaced appropriate distances apart.

103. A machine of the class described having, in combination, a last support, a tacker, and actuating mechanism including means for effecting a traveling movement of the tacker and also forth and back and inserting movements thereof while the last support remains substantially stationary.

104. A machine of the class described having, in combination, a last support, a tacker, means to actuate the tacker to insert fastenings, and mechanism to actuate the tacker forth to inserting position and back again, said mechanism having provision for varying the forward movement automatically according to the contour of the shoe edge.

105. A machine of the class described having, in combination, a tacker, a shoe support, means for actuating the tacker to insert tacks, means to move the tacker forth over the shoe to tacking position and then back again, means to effect traveling movement of the tacker to space the tacks, and means to effect angular movement of the shoe support to present different portions of the shoe bottom edge substantially perpendicular to the tacker.

106. A machine of the class described having, in combination, a reciprocating wiper, means for actuating it, a shoe support, means for positioning it angularly to present the shoe edge in predetermined angular relation to the path of the wiper, and means imparting to the wiper traveling movements in time relation to said positioning movements of the shoe.

107. A machine of the class described, having in combination, a wiper, means for actuating it, a shoe support, means to impart traveling movements to the shoe support, means to impart traveling movements to the wiper, said machine being arranged to cause operation of one of said last two means for a predetermined number of times and then to cause the other one to operate.
108. A machine of the class described, having in combination, a wiper, power driven means for actuating the wiper, and controlling means constructed and arranged to cause the wiper to stop after a predetermined number of operations.
109. A machine of the class described comprising upper overworking and securing means arranged to operate progressively around a shoe, a revoluble carrier that may be turned when desired, a plurality of jacks mounted thereon, each jack provided with a toothed plate, a plurality of pawl carriers having each a pawl to engage one of said toothed plates, combined with actuating means to operate first one and then the other of said pawl carriers according to which jack is to be rotated, a pawl controller, means to operate it to at times suspend the operation of one of said pawls when rotating said jack in order that said jack may remain at rest between each semi-rotation for a period of sufficient length to enable the upper along the straight sides of the last in the jack to be united to the innersole by said securing means, and means to hold the jack temporarily in position while the shoe sustained thereby is being operated upon, substantially as described.
110. In a machine of the class described, a jack having means to sustain a last, arms carried by said jack and bearing against the upper at the sides of the last, and other arms carried by said jack and having side clamps provided with flanges to bear against the upper at the junction of the side of the last with its bottom, the arms carrying the side clamps provided with flanges having thereon projections to overlap the arms which bear against the upper at the side of the last, whereby the movement of the arms which bear against the upper at the side of the last are made to actuate in one direction the arms carrying said side clamps provided with flanges, combined with upper uniting means having a nose to rest on said flanges during the time that the said means act to unite the upper to the innersole, substantially as described.
111. A machine of the class described, having in combination, a tacker, a shoe support movable to present the shoe to the tacker, means for locking the support in operative relation to the tacker, means for actuating the tacker to drive tacks, means for imparting to the tacker traveling movements to space the tacks, and means rendered effective for automatically moving the shoe support after a predetermined number of tacks have been driven.
112. A machine of the class described, having in combination, a wiper arranged to reciprocate forth and back repeatedly across the edge of a shoe, means for actuating it, means for stopping the wiper, and means for giving it a special movement of withdrawal.
113. A machine of the class described having, in combination, a work support, mechanism to insert fastenings in the work held on said support, and spacing mechanism adapted to impart a succession of intermittent movements to said inserting mechanism longitudinally of the work edge, and means to adjust said spacing mechanism to vary the distance which said inserting mechanism shall move in a step of the intermittent movement thereof.
114. A machine of the class described having, in combination, fastening inserting means, a work support and mechanism for relatively actuating the support and the inserting means to insert a series of fastenings on a curve corresponding substantially to the curved edge of the work, said mechanism including means to press the inserting means and the support laterally together, means to limit such movement according to the outline of insertion desired, and means to effect spacing movements of the inserting means.
115. A machine of the class described, having in combination a wiper, means for actuating it, a shoe support, means for imparting to the wiper a series of traveling movements to operate on successive portions of the upper along the side of the shoe, means to impart to the shoe support traveling movements to present successive portions of the toe or heel to the wiper, and means to impart to the wiper, during the traveling movements of the shoe support, return movements to its starting position.
116. A lasting machine comprising a shoe support and fastening inserting means, one having a rotating movement and the other a traveling movement in the line of the contour of the sole, said movements coöperating to produce relative travel of said fastening means about a shoe on said support.
117. A shoe support, traveling fastening inserting means, and means to move the latter to and fro with relation to the length of the shoe on said support and along the edge of the sole in the direction of its length to present fastenings successively at different points about the shoe.
118. An automatically rotatable shoe support, fastening means, and actuating means

to move said fastening means in opposite directions substantially parallel with the edge of the shoe carried by said support.

119. The combination with an automatically movable shoe support, of fastening inserting means, and means to impart thereto an in and out movement and also a traveling movement substantially parallel with the edge of a shoe on said support.

120. The combination with an automatically rotatable shoe support, of fastening inserting means, and means to impart thereto automatic in and out movement and also a traveling movement substantially parallel with the edge of a shoe on said support.

121. In a machine of the class described, automatically operating means for feeding and inserting fastenings, a suitable carrier, a plurality of individually rotatable last supports on said carrier, and means whereby said carrier is actuated to present said supports successively to said fastening means.

122. In a machine for use in making boots and shoes, means for feeding and inserting fastenings, a plurality of individually and automatically rotatable last supports, and means connecting said last supports and adapted to present the same successively to said fastening means.

123. An organized machine having, in combination, fastening inserting means, a plurality of rotatable last supports, means connecting said supports and adapted to present the same successively to said fastening means, and means arranged to coöperate with the support which is presented to said fastening means to the exclusion of the other support or supports for rotating the presented support automatically.

124. An organized machine having, in combination, fastening inserting means, a plurality of rotatable last supports, means connecting said last supports and adapted to present the same successively to said fastening means, means to rotate automatically said last supports when presented to said fastening means, and means to move automatically the said fastening means along the last support presented to it.

125. An organized machine containing a series of shoe supports, means to sustain said supports, means for holding the upper in condition to receive fastenings, fastening inserting means normally out of operative position with reference to said supports, means for rotating said shoe supports intermittently to bring different portions of the shoe successively into operative relation to the fastening means, and means to actuate said fastening means to drive fastenings singly into the shoe on that shoe support which is in the path of work of the fastening means.

126. An organized machine containing a

carrier provided with a series of shoe supports revoluble about an axis perpendicular to the top of the carrier, fastening inserting means normally out of operative position with reference to said supports, said carrier being movable to bring said shoe supports one after the other into operative position with relation to said fastening means, and means to rotate said shoe supports intermittently as said fastening means inserts fastenings one after the other into the upper and innersole.

127. An organized machine comprising automatic upper fastening inserting means, means to impart a traveling movement thereto in the line of the contour of the sole of the shoe, a shoe support, and means carrying said shoe support and adapted to move the same into and out of position to be acted upon by said upper fastening means.

128. In an organized machine, upper fastening inserting means, and automatic actuating mechanism for moving the same in the direction of the contour of the innersole of the shoe combined with a shoe support having end clamps to engage a lasted shoe and means for moving said support with its lasted shoe, whereby said fastening means will act to insert fastenings at intervals entirely about the edge of the innersole of said shoe.

129. An organized machine containing automatic upper fastening inserting means, a gage, a guide for said gage comprising toe and heel clamps, means whereby the same may be clamped about and upon the respective ends of a last and upper thereupon, side clamping means, and means to actuate the same.

130. A machine of the class described having, in combination, a shoe support, upper clamping means, upper fastening inserting means, means to impart thereto an in and out movement with relation to the edge of a shoe on said support, and an edge gage or feeler movably connected with said fastening means and adapted to contact at all times with said clamping means carried by the said shoe support.

131. The combination with a shoe support having a guide to encircle a shoe on said support, of an upper fastening inserting device, means to impart in and out movement thereto with reference to said support and guide, and a member adapted to follow and keep proper contact with said guide notwithstanding the in and out movement of said fastening device, said member and guide defining the extent of the inward movement of the fastening device and therefore the distance from the edge of the shoe at which the fastenings shall be applied.

132. A machine of the class described comprising a swinging fastening inserting mechanism, a shoe support, and means to

swing said fastening mechanism and also to impart to said fastening mechanism a rising and falling movement, and means to cause automatic relative traveling movement of said fastening mechanism and shoe support during the tacking of an upper to the sole of a shoe in timed relation to the swinging movement imparted to said fastening mechanism.

10 133. In a lasting machine, a shoe support, a carrier therefor, fastening inserting means, means to move the same automatically in and out bodily with relation to said support, a gage, and means co-acting therewith to determine the inward position of the fastening means at the completion of the inward movement thereof and thereby determine the distance from the edge of the innersole to be occupied by the line of 15 fastenings inserted in the upper to confine the same to the innersole.

134. In a lasting machine, the combination with a rigid wiper, of automatic actuating mechanism therefor constructed and arranged to cause said wiper to move in a path to engage the upper at the extreme edge of the last and to maintain said wiper in sliding engagement with the upper from such edge to the end of its inward 20 movement and out of contact with the upper upon its return movement.

135. The combination of a wiper, actuating mechanism therefor constructed and arranged to cause the wiper to engage the upper at the edge of the last, to maintain wiping engagement with the upper to the end of its inward movement, and to return out of engagement with the upper, 25 fastening inserting means, a shoe support, and means for imparting a relative feeding movement to the shoe support and wiper, said parts operating in timed relation.

136. A machine of the class described having, in combination, a tacker that comprises a driver casing and an upper wiping member and is mounted for oscillation in and out over a shoe bottom about a center that is located below the plane of the bottom of the shoe and back of the shoe whereby the 30 path of the tacker and the wiping member in going inwardly over the shoe is inclined downwardly, and means to actuate the tacker to insert tacks.

137. A machine of the class described having, in combination, a tacker that comprises a driver casing and an upper wiping member and is mounted for oscillation in and out over a shoe bottom about a center that is located below the plane of the bottom

of the shoe and back of the shoe whereby 60 the path of the tacker in going inwardly over the shoe is inclined downwardly, and means to cause the driver to insert a tack inclined inwardly while the wiper member is applying a maximum downward pressure 65 upon the overwiped shoe upper.

138. A machine of the class described having, in combination, a tacker, a wiper, mechanism for actuating the wiper inwardly across the edge of the shoe and 70 pressing it downwardly, and means for maintaining the wiper above the plane of the shoe bottom until it reaches the edge of the shoe and then permitting it to drop under said downward pressure upon the 75 shoe bottom to treat the shoe by impact preliminary to the insertion of a tack from the tacker.

139. An organized machine containing 80 automatic upper fastening inserting means, a guide constructed to conform to various contours of last and to press the lasted upper against the last, said guide presenting a top and outer side meeting in an exterior corner, and a yielding gage engaging said guide.

140. An organized machine containing 85 automatic upper fastening inserting means, means to sustain the last, a guide composed of jointed sections adapted to be changed 90 to conform to the various conformations of lasts, means to clamp said guide about and upon the upper on the sides of the last near its bottom, and a gage engaging the exterior of said guide and sustained upon the 95 upper edge thereof.

141. In a lasting machine, the combination with a wiper member, of actuating means to cause said member to travel in a path to engage the upper at the edge of the last, to maintain sliding engagement with the upper to the end of its inward movement and to return out of contact with the upper, a reciprocatory driver carried by said member, a shoe support, and means 100 to cause a relative traveling movement between said member and shoe support in timed relation to the wiping movements of said member.

In testimony whereof I have signed my 110 name to this specification in the presence of two subscribing witnesses.

HAROLD C. HUDSON,
Administrator of the estate of Thomas K.
Keith, deceased.
Witnesses:

ARTHUR L. RUSSELL,
HERBERT W. KENWAY.

Corrections in Letters Patent No. 1,030,819.

It is hereby certified that in Letters Patent No. 1,030,819, granted June 25, 1912, upon the application of Thomas K. Keith, deceased, late of Boston, Massachusetts, by Harold C. Hudson, Administrator, of Swampscott, Massachusetts, for an improvement in "Tacking Mechanism," errors appear in the printed specification requiring correction as follows: Page 4, line 94, for the word "drive" read *driver*; page 12, line 26, for the word "said" read *and*; same page, line 118, for the word "sides" read *side*; page 13, line 100, for the word "continuously" read *continually*; page 14, lines 33 and 34, for the word "tracker" read *tacker*; page 19, line 82, for the word "last" read *lasts*; and that the said Letters Patent should be read with these corrections therein that the same may conform to the record of the case in the Patent Office.

Signed and sealed this 24th day of September, A. D., 1912.

[SEAL.]

C. C. BILLINGS,
Acting Commissioner of Patents.
